UNITED STATES PATENT OFFICE.

BARTHOLOMEW P. BURNS, OF CHICAGO, ILLINOIS, ASSIGNOR OF ONE-HALF TO
DWIGHT B. CARMICHAEL, OF CHICAGO, ILLINOIS.

LOCKING DEVICE FOR COATS, HATS, AND UMBRELLAS.

1,116,989.

Specification of Letters Patent.

Patented Nov. 10, 1914.

Application filed July 9, 1913. Serial No. 778,169.

To all whom it may concern:

Be it known that I, BARTHOLOMEW P. BURNS, a citizen of the United States, residing at Chicago, in the county of Cook 5 and State of Illinois, have invented certain new and useful Improvements in Locking Devices for Coats, Hats, and Umbrellas; and I do hereby declare the following to be a full, clear, and exact description of the invention, such as will enable others skilled in the art to which it appertains to make and use the same.

This invention comprehends improvements in locking devices for hats, coats, and umbrellas, and relates more particularly to coin controlled means of this nature whereby after a coin is inserted into the device the latter may be locked to prevent the articles being taken by unauthorized persons.

20 One of the objects of the invention resides in the provision of a locking device of this nature wherein a key is used to release the retaining arms and simultaneously means are set in motion for locking the key within its case from which it may not be extracted until a coin has been dropped into the device.

Another object of the invention resides in the provision of a hat and coat hanger which 30 may be used to support the articles without first dropping the coin into the device, but which cannot be operated so as to lock the articles to the supporting hooks without payment of the necessary coin.

35 As a further object, the invention contemplates the provision of a novel device of this nature which shall be of extremely simple construction, cheap to manufacture, and which shall be a general improvement over devices of a similar nature now in use.

With these and other objects in view, as will become more apparent as the description proceeds, the invention consists in certain novel features of construction, combination, and arrangement of parts, as will be hereinafter described and claimed.

45 For a complete understanding of my invention, reference is to be had to the following description and accompanying drawings, in which,

Figure 1 is a vertical section partly in elevation, looking at the device from the rear, Fig. 2 is a similar view showing the arrangement of the parts when in their 50 locked positions, Fig. 3 is a section taken on

the plane of line 3—3 of Fig. 2, Fig. 4 is a horizontal section taken on the plane of line 4—4 of Fig. 2, Fig. 5 is a detail perspective view of the stop member, Fig. 6 is a detail view partly in section and partly in elevation, showing the connection between the sliding bars, Fig. 7 is a perspective view, showing one of the keys used in operating the device, Fig. 8 is a detail perspective view of a key used for unlocking the casing door, Fig. 9 is a detail perspective view of the clamping and releasing members, the key lock, and the lock for the casing door, Fig. 10 is a detail perspective view of the coin case, Fig. 11 is a fragmentary detail 60 view of one of the sliding bars, and Fig. 12 is a longitudinal section through the umbrella and cane receptacle.

Generally speaking, the device comprises a casing having hat and coat hooks formed 75 thereon; retaining arms for engagement with the articles supported upon said hooks; means for locking the retaining arms in their operative positions; key operated means for releasing the retaining arms; 80 means for locking the key within its case; a stop member for rendering the retaining arms inoperative until a coin is deposited within the coin guide; and means for locking an umbrella or cane.

The casing includes a front wall or face plate 15, side walls 16 and 17, and a bottom wall 18. The rear of the casing is closed by a door 19 which is hinged to the top 20 of the casing. This door carries a notched 90 locking arm 21 which operates, in a manner to be hereinafter described, for the purpose of holding the door in its closed position. A hat hook 22 extends laterally from the right hand edge of the face plate and a coat 95 hook 23 which is somewhat shorter than the hat hook also extends laterally from the face plate below the first mentioned plate. When it is stated that these hooks extend from the right hand edge of the face plate, 100 it is to be understood that the observer is standing in front of the device. This same fact is to be remembered whenever right or left is used in the specification.

Brackets 24 and 25 are secured within the 105 casing to the face plate 15 and are slotted to receive the sliding bars 26 and 27, the former of which has formed integrally therewith a coat retaining arm 28 which extends through a slot 29 formed in the right 110

side of the casing so as to hold garments upon the coat hook 23. The bar 26 is also provided with a forwardly projecting arm 30, which works through a slot 31 formed in the face plate 15 and which is provided with an operating knob or handle 32, whereby the sliding bar may be conveniently forced downwardly. To return this bar to its raised position, I provide a contractile 10 spring 33 which is attached at its lower end to the arm 28 and at its upper end to a lug formed upon the bracket 24.

The hat retaining arm 34 is pivotally secured at one end within the casing to the 15 front wall thereof, extends through a slot 35 formed in the top and side of the casing, and may be operated so as to hold a hat upon the hook 22. This arm is formed with a short straight portion adjacent its pivoted 20 end and with a curved portion 36, which extends downwardly over the hat hook. A connecting rod 37 which is essentially U-shaped, as clearly shown in Fig. 3, is secured at its upper end to the arm 34 and 25 extends at its lower end through the bar 27 into the slot 38 formed in the sliding bar 26. An expansive spiral spring 39 is positioned within the slot 38 between the end of the link 37 and the top of said slot. This 30 form of connection between the two sliding bars is for the purpose of accommodating the device to different thicknesses of coat collars. For instance, should a very thin wrap be hung upon the hook 23 and the 35 handle 32 pulled downwardly, the arm 36 will first come into contact with the hat hook 22 and then the spring 39 will contract and permit of the arm 28 tightly engaging the wrap. It will be evident that a downward 40 movement of the bar 26 by means of the handle 32 will cause a corresponding movement of the bar 27 because of the spring connection and the bar 27 being connected by a link 37 to the arm 34 will cause 45 a downward movement of the latter.

In order to provide for locking the sliding bars in their lowered positions, I provide the clamping arms 40 and 41, which engage the bars 26 and 27, respectively. To 50 support the clamping arms, I provide a frame, generally designated 42, which includes a base 43, vertical arms 44 extending upwardly from the front and rear edges of the base, a pivoted rod 45 supported in a 55 horizontal plane by the upstanding arms, and side walls 46 and 47. The clamping arms are pivoted upon the rod 45 and are provided with the depending arms 48 which are formed with the rearwardly extending 60 projections 49, clearly shown in Fig. 4. These projections extend through openings formed in the side wall 47 and are encircled by expansive spiral springs which tend to normally force the arms 48 toward the right 65 side wall 46. When the sliding bars are

drawn downwardly, they strike the beveled ends of the clamping arms and ride beyond the same, swinging the arms a slight distance downwardly. The springs 50 hold the clamping arms into engagement with the 70 sliding bars so that the bars cannot be raised until the arms are swung away from contact therewith. By referring to Fig. 2, the manner in which the clamping arms operate will be apparent.

To release the clamping arms from engagement with the sliding bars, I make use of the key such as is shown in Fig. 7. This is inserted into the casing through an opening in the front wall thereof and extends 80 into the key case 51, which, as is clearly shown in Figs. 1 and 3, is formed by a left side wall 52 and the right side walls 53 and 54, the latter being notched to permit the passage of the lugs 55 formed upon the 85 shank of the key. By varying the number and position of the notches and lugs various key combinations may be secured so that no key will fit more than one case. When the key is rotated within the case, the angular 90 arm 56 will be carried through the angular slot 57 into engagement with the releasing arms 58 formed upon the lower extremities of the depending arms 48. These releasing arms extend through slots formed in the 95 wall 46 and normally extend into the horizontal portion of the slot 57. The shoulders formed upon the extremities of the releasing arms prevent the latter extending entirely through the slot 57. The key arm 100 56 coming into engagement with the releasing arms forces them toward the right side of the casing and it causes the clamping arms 40 and 41 to swing downwardly and release the sliding bars 26 and 27. The 105 spring 33 will then operate to raise said bars and remove the retaining arms from engagement with the hat and coat.

It is necessary that some means be provided for locking the key within the key 110 case after the retaining arms have been raised so that the next person to use the device will find the key in its position from which it can only be removed when the device is in operation. To accomplish this 115 end, I provide a locking member comprising an arm 59 which is journaled upon the rod 45 and which is provided with a depending arm 60 which carries upon its lower extremity the key lock 61. When the sliding 120 bars are raised the key lock 61 is forced into the key case through the opening 62 by means of an expansive spiral spring 63 carried by the projection 64, which latter extends through an opening formed in the 125 wall 47. When the key lock 61 is extended through the key case the key cannot be withdrawn because the angular arm 56 cannot be drawn past the key lock. When the sliding bars are drawn downwardly, so as to 130

bring the retaining arms into operative position, they engage the arm 59 as shown in Figs. 2 and 4, and depress the free end thereof so as to withdraw the key lock 61 from the key case 51 and permit of the key being withdrawn from the case. The key may then be kept in possession of the user of the device until he desires to release the retaining arms and unlock the locked articles. In doing this the key must be inserted in the key case and turned as before described so as to withdraw the clamping arms from the sliding bars and as these bars are carried upwardly, the key lock will be forced into the key case.

In order to make it necessary to deposit a coin within the device before it can be operated, I employ a coin case or guide, generally designated 65 and clearly shown in Fig. 10 and a coöperating stop member. The coin case is secured to the front wall 15 of the casing, which latter is provided with a slot 66 into which the coin is dropped. The stop member, including a depending plate 67, is pivotally secured to the laterally extending lug 68 formed upon the sliding bar 26 adjacent its upper end and hangs essentially parallel to the coin case. This plate, as clearly shown in Fig. 5, is formed adjacent its rear edge with a laterally extending lug 69 having the inclined edges 70 and 71 and the horizontal lower edge 72. A finger 73 is formed adjacent the front edge of the plate 67 at its lower extremity. The coin case is formed with an opening 74 having a horizontal lower edge 75 for engagement by the bottom edge 72 of the lug 69 when the latter is forced into the coin case. The finger 73 extends into the coin case and may be moved downwardly into the slot 76. When the sliding bars 26 and 27 are in their raised positions, the lug 69 engages the side of the coin case above the opening 74 and the finger 73 extends into the casing and across the case, as is shown in Fig. 1. The stop member is forced toward the coin case by means of the expansive spiral spring 77 which is carried upon the arm 78 formed upon the sliding bar 26. This arm extends through an opening 79 formed in the plate 67.

When an attempt is made to draw the retaining arms into operative position without first placing a coin in the coin case, the lug 69 is forced into the opening 74 sufficiently far to bring the lower edge 72 of the lug directly over the edge 75 of the opening and prevent the bar 26 being lowered beyond a certain limited distance. When a coin is dropped within the coin case through the opening 66, it rests upon and is supported by the finger 73 and when the bar 26 is drawn downwardly the coin prevents the lug 69 being forced into the coin case far enough to bring the lower edge

72 in the path of the bottom 75 of the opening 74. When the sliding bars have reached the limit of their downward movement, the finger 73 is at the lower extremity of the slot 74 and the coin will ride out through the opening 80. On the upward movement of the stop member, the inclined edge 70 of the lug will cause the latter to ride out of the opening 74 into the position shown in Fig. 1.

Any suitable means, not shown, may be provided for the reception of the coins as they fall from the coin case.

The door 19 of the casing is locked in its closed position by the swinging latch member 81 which is pivoted on the bar 45 and which is formed with an enlargement adjacent its lower end, as indicated at 82, which is received within the notch formed in the locking arm 21 of the door. When the door is closed the beveled extremity of the arm 21 strikes the projection or enlargement 82 and swings it to one side. Then the expansive spiral spring 83 which surrounds the projection 84 forces the enlargement 82 into the notch of the locking arm. When it is desired to unlock the door a key 85 which is clearly shown in Fig. 8, is inserted into a key case and turned so as to cause the projection 86 to extend through the slot 87 into engagement with the arm 88 and force the enlargement 82 out of the notch in the locking arm. The arm 88 is prevented from being projected through the opening 87 by the lug 89 which engages the side wall 52 of the key case.

To provide for locking umbrellas, canes, etc. to the device, I extend the bottom 18 of the casing downwardly to form a rear wall 90. As shown in Fig. 3, the wall 90 is of a less width than the bottom 18 and is attached to one side thereof. Side plates 91 and 92 are formed upon the wall 90 and extend at right angles thereto. A connecting rod 93 is secured at its upper end to the retaining arm 34 and extends downwardly and connects with a crank arm 94 formed upon the rod 95. This rod is journaled upon the exterior of the plate 92 and the crank arm extends inwardly through the slot 96. A locking bar 97 is rigid with one extremity of the rod 95 and is adapted to bridge the opening between the plates 91 and 92, as clearly shown in Fig. 3. When the retaining arm 34 is swung downwardly, the connecting rod 93 turns the crank arm 94 and rod 95 so as to swing the locking bar across the opening formed between the two plates 91 and 92. A receptacle 98 shown in Fig. 12 is suspended upon the rod 99 which is connected at its upper end to the wall 93. When the lower end of the umbrella is inserted within the receptacle 98, the upper end swung under the casing 18, and the bar 97 lowered, the umbrella

is locked securely. It cannot be moved upwardly because of the bottom of the casing, it cannot be moved downwardly because of the receptacle 98, and it cannot be moved outwardly from between the plates 91 and 92 because of the locking bar 97.

Although it is thought that the operation of the entire device will be clearly understood from the foregoing description, it might be well to state briefly the steps to be followed and the movements which take place after a coin has been placed into the device. The coin drops upon the finger 73 of the stop member and then when the handle 32 is pulled downwardly, the lug 69 will not engage in the opening 74 of the coin case but will pass beyond the same and allow the sliding bars 26 and 27 to be moved downwardly into engagement with the clamping arms 40 and 41. This downward movement of the clamping arms will bring the retaining arms 28 and 36 into an operative position and will also cause the locking bar 97 to be lowered. A hat, coat, and umbrella will now be securely locked to the device and the key may be removed from the key case and retained by the user until he desires to remove his articles from the device. To accomplish this last operation the key is inserted into the key guide and turned so as to release the clamping arms from engagement with the sliding bars 26 and 27. The coil spring 33 will then raise these bars into the position shown in Fig. 1.

From the foregoing description taken in connection with the accompanying drawings, it will be evident that I have provided a hat, coat, and umbrella locking device into which a coin must be deposited in order that the device may be operated so as to lock the articles thereto.

It is to be understood that while I have shown and described the preferred embodiment of my invention, I do not wish to be limited to this exact construction, combination, and arrangement of parts, but may make such changes as will fall within the spirit and scope of the invention as defined by the appended claims.

Having thus described my invention, I claim:—

1. In a device of the character described, a pair of stationary hooks, a pivoted retaining arm adapted to swing into engagement with one of the hooks, a sliding bar, a retaining arm carried by said bar and adapted to engage the other stationary hook, a link connecting the first mentioned retaining arm with the sliding bar, and means for locking the bar so as to hold the retaining arms in engagement with the stationary hooks.

2. In a device of the character described, a stationary hat hook, a stationary coat hook, a pivoted retaining arm for engage-

ment with the hat hook, a plurality of sliding bars, a second retaining arm carried by one of the sliding bars for engagement with the coat hook, said last mentioned sliding bar being formed with a longitudinal slot, 70

a link connected at one end to the first mentioned retaining arm and extending through one of the sliding bars into the slot formed in the other sliding bars, an expansion member interposed between the end of the link 75 and one end of the slot, and means for locking the bars so as to hold the retaining arms in engagement with the stationary hooks.

3. In a device of the character described, a casing having stationary hooks extending laterally therefrom, a retaining arm pivoted to the casing for engagement with one of the hooks, a longitudinally movable bar, a second retaining arm carried by said bar for engagement with the other stationary hook, 85 a second longitudinally movable bar parallel with the first bar, a link connected at one end to the first mentioned retaining arm and extended angularly at its other end through a transverse opening formed in the second 90 mentioned longitudinally movable bar, a yielding connection between the link and the first mentioned longitudinally movable bar, and means for locking said bars so as to hold the retaining arms in engagement with the 95 stationary hooks.

4. In a device of the character described, a longitudinally movable bar, a pivoted clamping arm projecting into the path of the said bar, the arm holding the bar against movement in one direction, a releasing arm carried by the clamping arm, and a key for engagement with the releasing arm whereby the clamping arm will be moved from engagement with the sliding bar. 100

5. In a device of the character described, a pair of sliding bars, pivoted clamping arms projecting into the path of said sliding bars and adapted to lock the bars against movement in one direction, depending shanks 110 formed upon the clamping arms, release arms formed upon said shanks, a key case having openings formed in one wall thereof, spring means for forcing the release arms toward said openings, and a key adapted to be inserted within the key case and turned so as to engage the release arms and move the clamping arms from engagement with the sliding bars. 115

6. In a device of the character described, a pair of longitudinally movable bars, a pair of pivoted clamping arms projecting into the path of said bars, to lock the same against movement in one direction, a pivoted key locking member also extending into the path of said bars, a key case having openings in one side thereof, a key having an angular arm, release arms connected to the clamping arms, and said key adapted to rotate causing said release arms to move the clamping arms 120 125 130

from engagement with the sliding bars, the upward movement of the sliding bars allowing the locking arm to slide into the key case in the path of the angular key arm.

5 7. In a device of the character described, a pair of sliding bars, a pair of clamping arms adapted to hold the bars against movement in one direction, depending shanks carried by the clamping arms, release arms 10 formed on said shanks, a key case having openings formed in one side thereof, spring means for forcing the release arms into certain of said openings, a key lock including an arm projecting into the path of the sliding bars, a shank, and a key locking bar; said sliding bars adapted to move downwardly to move key locking arm away from the key case, and a key having an angular arm adapted to engage the release arms to

swing the clamping arms away from sliding 20 bars, said sliding bars adapted to move upwardly causing the key locking arm to extend within the key case.

8. In a device of the character described, a casing, a frame positioned under said casing, a receptacle located below said frame to support articles projecting through the frame, a pivoted member mounted within the casing and means operated by said pivoted member to lock articles within the 30 frame.

In testimony whereof I affix my signature in presence of two witnesses.

BARTHOLOMEW P. BURNS.
